(57) **CLAIM**

The ornamental design for a blow off valve for automobile, as shown and described.

DESCRIPTION

FIG. 1 is a perspective view of a blow off valve for automobile showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The dash-dash broken lines in the drawings illustrate portions of the blow off valve for automobile that forms no part of the claimed design. The dash-dot broken line in FIG. 6 depicts the disclaimed boundary of the claimed design.
